UNITED STATES PATENT OFFICE.

JOSEPH W. WOHLHETTER, OF NEWARK, NEW JERSEY.

TRIANGLE CHAIR BRACE.

Application filed December 20, 1922. Serial No. 607,942.

To all whom it may concern:

Be it known that JOSEPH W. WOHLHETTER, citizen of United States, residing at Newark, in the county of Essex and State of New Jersey, has invented certain new and useful Improvements in Triangle Chair Braces, of which the following is a specification.

This invention relates to furniture, and has special reference to a chair brace for bracing the legs and stretchers of chairs firmly together.

While the invention has been designed for furniture, it is obvious that it can be successfully applied to anything requiring bracing from three different angles or positions. Specifically the present embodiment relates to a triangular chair brace for bracing a leg and two of the converging stretchers of wicker chairs together to form a unitary structure.

In the construction of wicker chairs, the stretchers, at the front and sides, are made to converge to a common point on the leg. The reason for this is that these stretchers are used to support the seat formed by the wicker or reed, and it is thus necessary that the edges of the reed work be at the same level, to preserve the substantial flatness of the seat of the chair, sofa, or other similar article. On account of the necessity of these stretchers being on a common level on the leg, it is impossible to mortise and tenon the ends of the stretchers which are usually of substantially the same diameter as the leg, or nearly of that diameter, in the leg without so weakening the latter that it will readily break off. The usual manner of fastening such stretchers to the chair leg is to pass a screw diametrically through the leg, and into the end of the stretcher. Under these conditions, the joint which is made in this manner is weak, and is apt to, under the stresses incident to use, fail by the screw pulling out of the end of the stretcher.

The principal object of the present invention is to provide a triangular or three-cornered brace which will not only connect each of a pair of converging stretchers to the leg, but will also brace these stretchers together.

A second important object of the invention is to provide a brace of this character which is so constructed that the ends of the

brace will lie flat on the stretchers and leg of the chair so that the winding of the reed or wicker work around the leg and stretchers may be, to all intents and purposes, smooth and unbroken, such winding passing over the flat attaching ends of the brace without making an unsightly bulge or projection.

A third important object of the invention is to provide a brace of this character wherein the brace members themselves will be very stiff and strong, while the connection to the stretchers and leg will be such as to permit of winding continuously along the leg, this being effected by the peculiar construction of the brace at its junction to the leg.

A fourth important object of the invention is the provision of a new article of manufacture stamped from sheet or plate metal, and shaped to form an improved three-cornered or triangular brace for the purpose described.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a perspective view of a corner of a chair frame showing the manner of using the triangular brace.

Fig. 2 is a plan view of such brace.

Fig. 3 is a section on the line 3—3 of Fig. 2.

Fig. 4 is a longitudinal section through a portion of one of the chair members and a corner of the brace showing the close manner in which the wicker wrapping is positioned on the chair member.

In the embodiment of the invention herein illustrated, the same has been shown as applied to a chair corner wherein the leg of the chair is indicated at 10, and a pair of stretchers 11 and 12 are shown as converging and meeting the leg at a common level above the bottom of the leg. The manner of securing these stretchers is indicated at 13 by the screw head there shown.

The brace itself forming the subject matter

— of this invention, is stamped from a single piece of sheet steel of suitable thickness, and of general triangular form, the corners of the triangle being rounded off as at 14, and 5 the interior of the triangle being cut out to present a substantially triangular space 15.

The triangle thus formed is preferably an equilateral triangle, and the metal of its legs 10 is bent transversely to trough shape intermediate the ends. The metal on each angle of the triangle is flattened out as at 17, and is then bent to form a short trough 18 angularly disposed with reference to the flattened portions 17, and provided with a suitable 15 nail, or rivet receiving opening 19. This short trough 18 is curved in the direction opposite the trough shaped central portions of the legs of the triangle, and its curvature is such that it will, when in position on the 20 chair, fit snugly on the stretcher or leg, as the case may be, so that the rivets 20 may be passed through the openings in the apices of the triangle to secure these apices to the respective parts of the chair. By reason of 25 the trough or channel shape formation between the apices, the device is exceedingly stiff for its weight, and owing to the three bracing elements, each of which is formed by one side of the triangle, being integral, 30 but three rivets 20 are necessary for placing the device in position on the chair.

Another feature that is of importance rests in the manner in which the flattened portions 17 are disposed at an angle to the 35 short troughs 18. With the construction thus made, the short troughs 18 fit snugly on the chair members so that the wicker wrapping can be carried right over them without producing any unsightly bulge or projection, 40 while the angularly disposed flat portions permit the wicker wrappings to be made continuously along the chair member without any breaking or interruption of the winding exposing the wooden chair member between 45 the wrappings.

In the manufacture of these devices, the three-cornered braces may be made by stamping and pressing from ordinary sheet metal, a cutting die being used to form the blank, and the latter then being simply pressed to 50 shape in suitable dies.

There has thus been provided a simple and efficient device of the kind described and for the purpose specified.

It will be noted that by reason of the semi-circular formation of the brace between the corners of the triangle, and by reason of the position of the brace on the chair, the brace 55 may be covered by wicker winding and present a proper and rounded appearance in the absence of a skirting which will not interfere with the harmonious design of the chair. Furthermore, this round prevents sharp bends being made in the wicker work 60 which would tend to break it when so wound.

Having thus described the invention, what is claimed as new, is:

1. A brace for connecting the leg of a chair, to a pair of chair stretchers, and comprising a triangular member having the 70 apices of the triangles angularly disposed with reference to the body of the triangle and bent to form trough shaped portions adapted to seat respectively on the leg and stretchers, said trough shaped portions being provided with rivet receiving openings. 75

2. A brace for connecting the leg of a chair to a pair of the chair stretchers, and comprising a triangular member having the 80 apices of the triangles angularly disposed with reference to the body of the triangle and bent to form trough shaped portions adapted to seat respectively on the leg and stretchers, said trough shaped portions being provided with rivet receiving openings, 85 the central portion of said brace being cut away and the legs between the open center and the periphery of the triangle being bent to trough shape in a direction opposite the first mentioned trough shaped portion. 90

3. As a new article of manufacture, a three-cornered chair brace cut and stamped from a single piece of sheet metal, said chair brace being formed from a triangular blank having a triangular opening in its center 95 with the sides of the opening and the blanks substantially parallel, said blanks being stamped to form trough shaped legs connecting the apices of the triangle, the metal on the apices being flattened and formed to 100 constitute terminal troughs angularly to the flattened portions and curved in a direction opposite to the curvature of the legs, said terminal troughs being provided with rivet receiving openings. 105

4. In a brace for furniture, a unitary body of closed triangular shape, the three apices of which are perforated and equally spaced relatively to each other, the said body having its medial portion cut away for providing three arms of equal length, and the said arms intermediate the apices being rolled for stiffening the arms, and the perforated portions of said body being offset and formed with seats to conform to the 110 surfaces of a chair and the like to which the brace is applied.

5. A corner brace for furniture, comprising a triangular body having its central portion cut away for providing three arms of 115 equal length and breadth, the portions of the body adjacent the intersection of the arms being perforated to receive attaching devices, and the said perforated portions being formed with seats for conforming to the surfaces of the legs and rails of furniture, and the medial portions of said arms being partially rolled for stiffening said portions. 125

6. A furniture corner brace comprising a three-sided integral body having each side 130

length transversely contracted to provide for lengthwise reinforcement thereof, the corners of said body being deflected to one side of the plane of the body and transversely 5 dished to form corner seats.

7. A furniture corner brace comprising a triangular body having an open center, the sides of said body being bowed transversely with the inner edges merging into one another and the outer edges extended outwardly at the corner to form attaching tabs.

8. As an article of manufacture, a furniture corner brace comprising an equilateral three-sided body, having its sides substantially 15 in the same plane and spaced from the corner of the furniture, and the points of intersection of the sides formed to seat

on the frame members of the furniture at points spaced from the corner.

9. In combination with an article of furniture having a corner formed by three converging frame members, of a substantially flat brace body secured to the three frame members at points spaced from the corner and lying in a plane cutting the three frame 20 members and forming the base for a pyramid formed by the three frame members.

In testimony whereof I affix my signature in presence of two witnesses.

JOSEPH W. WOHLHIEDER.
